VEHICLE WHEEL WEDGE OR SIMILAR ARTICLE

Joseph W. E. Whitright, Cheshire, Conn., assignor to
Cheshire Manufacturing Co., Inc., Cheshire, Conn.,
a corporation of Connecticut

Filed Feb. 19, 1968, Ser. No. 10,636

Term of patent 14 years

(Cl. D41—1)

FIG. 1

FIG. 2

FIG. 3

FIG. 4

FIG. 5

FIG. 6

FIG. 1 is a perspective view of a vehicle wheel wedge or similar article showing my design;

FIGS. 2, 3, 4 and 5 are front, rear, right side and bottom views, respectively, thereof; and

FIG. 6 is a vertical cross-section taken on the line 6—6 of FIG. 4.

I claim:

The ornamental design for a vehicle wheel wedge or similar article, substantially as shown.
